RAILWAY TRUCK

Donald L. Townsend, Rochester, N. Y., assignor
to The Symington-Gould Corporation, a cor-
poration of Maryland

Application January 2, 1934, Serial No. 704,958

26 Claims. (Cl. 267—3)

This invention relates to railway trucks and, more particularly, to nests of springs for supporting truck bolsters, and the spring plates for said nests.

5 The principal object of my invention, generally considered, is the provision of railway trucks in which the bolsters are supported from associated side frames by means of nests of springs involving leaf or elliptic springs associated with 10 helical or coil springs, and employing improved spring plates, preferably formed of cast metal, or other cast means, for holding the springs and the nests in proper relation with respect to one another and the associated frame, said plates being particularly adapted to more positively 15 retain the bands of the elliptic or leaf springs in normal position.

Another object of my invention is the provision of cast spring plates or caps adapted for 20 use with nests of springs involving both elliptic or leaf springs and helical or coil springs.

Other objects and advantages of the invention relating to the particular arrangement and construction of the various parts will become apparent as the description proceeds.

Referring to the drawings illustrating my invention, the scope whereof is defined by the appended claims:

Figure 1 is a fragmentary side elevational view 30 of a railway truck embodying my invention.

Figure 2 is an elevational view, with the upper spring plate shown in vertical section, and the adjacent set of helical springs removed, of the nest of springs shown in Figure 1 detached from 35 the truck and looking in a direction at right angles to that of Figure 1.

Figure 3 is a plan of the nest of springs shown in Figures 1 and 2, a portion of the upper spring plate being broken away and the associated helical springs only fragmentarily illustrated.

Figure 4 is a detail plan, on a larger scale, of one of the interchangeable spring plates shown in Figures 1, 2 and 3.

Figure 5 is a partial end elevation and partial sectional view on the line 5—5 of Figure 4, looking in the direction of the arrows.

Figure 6 is a partial side elevation and partial vertical sectional view on the line 6—6 of Figure 4, looking in the direction of the arrows.

Figure 7 is a fragmentary sectional view on the line 7—7 of Figure 4.

Figure 8 is a fragmentary sectional view on the line 8—8 of Figure 4.

55 Figure 9 is a fragmentary plan of a spring plate

such as shown in Figure 4, but illustrating another embodiment of my invention.

Figure 10 is a partial elevational view and partial vertical sectional view on the line 10—10 of Figure 9, looking in the direction of the arrows. 5

Figure 11 is a fragmentary sectional view on the line 11—11 of Figure 9, looking in the direction of the arrows.

Figure 12 is a fragmentary sectional view on the line 12—12 of Figure 9. 10

Figure 13 is a fragmentary sectional view on the line 13—13 of Figure 9.

Figure 14 is a view showing a developed profile of a helical spring centering rib or flange from the point A to the point B, as shown in Figure 9. 15

Figure 15 is a fragmentary plan corresponding to Figure 9, but illustrating another embodiment of my invention.

Figure 16 is a fragmentary view, partly in elevation and partly in section, on the line 16—16 20 of Figure 15, looking in the direction of the arrows.

Figure 17 is a fragmentary sectional view on the line 17—17 of Figure 15, looking in the direction of the arrows. 25

Figure 18 is a fragmentary plan corresponding to Figure 15, but showing a further embodiment of my invention.

Figure 19 is a fragmentary sectional view on the line 19—19 of Figure 18, looking in the direction of the arrows. 30

Figure 20 is a fragmentary plan corresponding to Figure 18, but showing an additional embodiment of my invention.

Figure 21 is a fragmentary sectional view on the line 21—21 of Figure 20, looking in the direction of the arrows. 35

Figure 22 is a fragmentary sectional view on the line 22—22 of Figure 20, looking in the direction of the arrows. 40

Figure 23 is a fragmentary plan corresponding to Figure 20, but showing another embodiment of my invention.

Figure 24 is a partial elevational view and partial vertical sectional view on the line 24—24 of Figure 23, looking in the direction of the arrows. 45

Figure 25 is a fragmentary elevational view of the spring plate shown in Figure 23, looking from the left.

Figure 26 is a fragmentary sectional view on the line 26—26 of Figure 23, looking in the direction of the arrows. 50

Referring to the drawings in detail, like parts being designated by like reference characters, and first considering the embodiment of my invention. 55

tion illustrated in Figures 1 to 8, inclusive, there is shown a portion of a railway truck involving a pair of side frames 2, only one of which is illustrated, receiving the ends of a bolster 3, only one end of which is illustrated. The bolster 3 extends into the window openings 4 of the frames 2, each window opening being defined by a compression member 5, a tension member 6, and bolster guide columns 7. Supported at each end on the tension member of a frame beneath the window openings 4, in the present embodiment, is a spring plank 8 between each end of which and each corresponding end of the bolster 3 is a nest of springs 9 disposed in the corresponding window opening 4.

- 15 In the present embodiment, each nest of springs 9 comprises four helical or coil springs or spring units 10 and an elliptic or banded leaf spring, or series of leaf springs held together by bands, 11. Each spring 11, in the present embodiment, 20 comprises a stack or series of curved spring leaves 12 held together intermediate their ends by bands 13, the outer surfaces of which may be slightly convex to correspond with the curvature of the secured leaves, and divided into upper and lower 25 groups, with their end portions separated by end blocks 14, in accordance with the usual practice for full elliptic springs.

In order to center or hold the elliptic and coil springs in proper position between the bolster 30 and spring plank, or bolster and frame, if the spring plank is omitted, I employ preferably interchangeable upper and lower cast spring caps or plates 15 and 16, said plates being formed to surround or partially house the spring bands, as well 35 as being provided with collars 17 extending toward the collars on the associated plate, and normally surrounded by the associated coil or helical springs for centering purposes. The spring plates also directly engage the adjacent 40 ends of the coil springs, and are thicker at these places than the remaining web portions of the plate, thereby providing elevating seats for said springs which are closer to one another than the seats for the elliptic spring bands, thereby avoiding 45 over-stressing the leaves of said elliptic spring or allowing for a greater travel of said spring than would otherwise be permissible.

Each plate or cap 15 and 16 comprises the relatively thick corner portions 18 which serve as the 50 seats for the helical springs 10, as previously mentioned. In the present embodiment, the collars or flanges 17 extending from said seats for centering the helical springs 10 are defined by apertures 19 which flare both ways from the face of the plate 55 from which said collars extend, as illustrated most clearly in Figure 7, thereby conserving material and at the same time maintaining adequate strength. The thickened portions 18 of the plate are for the same reasons desirably relieved by 60 grooves 20 immediately surrounding the collars 17.

The corner portions 18 are desirably flattened at the sides, as indicated at 21, so that they will fit between the upstanding flanges 22 of the associated spring plank 8 with the desired clearance. The web 23 of the plate 15 or 16, as the case may be, between the corner portions 18, is desirably thinner than the corner portions, but made adequately strong by ribbing, generally indicated by 65 the reference character 24, thereby conserving material. The central portion of the ribbing 24 is generally rectangular, as indicated at 25, and the web portion 23 surrounded by the rectangular ribbing 25, which forms lateral restraining means 70 for the associated band 13, is still thinner in

general than the web portions outwardly thereof, the upper surface of said web 23 being desirably concave to match the engaging surface of the spring band 13.

The rectangular band positioning rib or flange 5 25 comprises generally straight side portions 27 which correspond in height with the thickness of the band and extend distances corresponding with the width of the spring leaves or leaf springs of said elliptic spring 11. Said straight portions 27 10 have their ends joined by portions 28 which are considerably higher than the portions 27, as they may be on account of being beyond the sides of the leaves of said elliptic spring 11. Said higher portions 28 comprise not only end portions but 15 angular extensions aligned with the lower side portions 27, whereby the corner portions of each band are engaged by relatively tall centering ribs or flanges, the extreme end portions of which are adapted to engage the sides of the adjacent 20 spring leaf, whereby the elliptic or banded leaf spring is efficiently centered or held in proper position.

Reinforcing ribbing or flanges desirably extend outwardly from the ends of the relatively tall 25 ribbing 28 and curve to substantially align with the diagonals between opposite spring centering collars 17, where they unite with the relatively thick corner portions 18, as indicated at 29. Ribbing 30 also extends generally tangent to the 30 generally circular corner portions 18 and parallel to the corresponding diagonals between opposite spring centering collars 17 with the inner ends united by curved sectors 31. Exterior of said ribbing 30 and 31 are gussets 32 which are desirably provided to carry the spring plate centering 35 nibs 33.

Outwardly of the ribbing 28 and 29, the web 23 of each plate is desirably extended diagonally 40 upward or from the normal plane of the plate in the direction of the centering collars and ribbing, as indicated at 34, so as to provide for properly nesting with corrugations 35 in the spring plank 8, which corrugations are formed to provide for interlocking of said plank with the auxiliary reinforcements 36 which are disposed in the lower corners of the window opening 4, as described and claimed in the Barrows Patent No. 1,652,808 of December 13, 1927, or directly with said reinforcements upon omission of the plank. The 50 bolster, plank, or frame-engaging surface of each plate is desirably generally flat, as illustrated, thereby providing a satisfactory shimming surface.

Referring now to the embodiment of my invention illustrated in Figures 9 to 14, inclusive, there is disclosed a cast spring plate 15* which is only fragmentarily illustrated, as said plate is symmetrical about the center line represented by the upper element of the section line 10—10. The 60 plate 15* differs from the plate 15 of the previous embodiment, in that the corner portions 18* serve to center associated helical springs by peripheral preferably serrated ribbing 17*, which may be entirely discontinued where the corner portions 65 are flattened at the sides, as indicated at 21*. The manner in which the centering flanges 17* are serrated is shown most clearly in Figure 14 which illustrates a developed profile. As in the preceding embodiment, the corner portions 18* 70 are thicker than the connecting web portion 23* and the thickened portion 18* is desirably provided with relief grooves 20* and apertured at 19*. In the present embodiment, the central portion of the web 23* is formed with a generally

rectangular rib 25^a which serves for centering or positioning an associated elliptic spring by surrounding the engaged band thereof. The web portion 26^a inside of said rectangular ribbing is 5 preferably generally thinner than the web portions outside of said ribbing and is desirably concave to match the engaging surface of an associated spring band.

As in the preceding embodiment, the rectangular band positioning rib or flange 25^a comprises generally straight side portions 27^a which correspond in height with the thickness of the band and extend distances corresponding with the width of the spring leaves of the associated elliptic spring. The straight portions 27^a have their ends joined by portions 28^a corresponding with the portions 28 of the preceding embodiment, which, in turn, are joined by curved portions 29^a to the thickened portions 18^a, as in the preceding embodiment.

As in the preceding embodiment, the web 23^a of each plate 15^a outwardly of the portions 28^a and 29^a is desirably extended diagonally upward or from the normal plane of the plate in the 25 direction of the centering ribbing, as indicated at 34^a, so as to provide for properly nesting with corrugations or reinforcements, as in the preceding embodiment. The edges of the plate between the corner portions are desirably rigidified 30 by ribbing or flanges 30^a which connect the adjacent ends of the serrated helical spring encircling ribs at the inclined portions 34^a of the plate in the same way the edges of the plate are reinforced by peripheral ribbing 31^a between the 35 serrated flanges 17^a along the portions of the web 23^a outwardly of the ribbing 27^a.

Referring now to the embodiment of my invention illustrated in Figures 15, 16 and 17, there is disclosed a cast spring plate 15^b which is only 40 fragmentarily illustrated as said plate is symmetrical about the center line represented by the section line 17—17 and the upper element of the section line 16—16. The plate 15^b differs from the plate 15 of the first embodiment in that both 45 the corner portions 18^b have helical spring centering collars 17^b and, while thicker than the web 23^b of the plate, they do not have the relief grooves around the collars, and the ribbing 31^b is at the edge of the web portion instead of between said web portion and a gusset outwardly 50 thereof. The edge of the web portion 23^b is also rigidified by peripheral ribbing 30^b extending around the diagonal portion 34^b as in the embodiment of Figures 9 to 14, inclusive.

55 As in the first embodiment, rectangular ribbing 27^b, 28^b is provided for centering an associated elliptic spring by surrounding the band thereof, but the web portion 26^b surrounded by said ribbing is of the same thickness as the web 60 portion 23^b outwardly thereof and is flat rather than being cylindrically concave on its upper surface. In the present embodiment, the ribbing 28^b is extended straight outwardly and tapered in depth to merge into the web 23^b, as indicated at 65 29^b, rather than curving and extending to the thickened corner portions 18^b. Except as specifically described, the plate of the present embodiment may correspond with that of Figures 1 to 8, inclusive.

70 Referring now to the embodiment of my invention illustrated in Figures 18 and 19, there is disclosed a cast spring plate 15^c, which is only fragmentarily illustrated, as said plate is symmetrical about the vertical center line illustrated and the horizontal center line represented by the section

line 19—19. The plate 15^c is substantially identical with the plate 15^a of the embodiment of Figures 9 to 14, inclusive, except that there is no flattening of the thickened corner portions 18^c sufficient to cut away the peripheral spring positioning ribbing 17^c. A further distinction resides in the fact that the curved ribbing 29^c connects the ends of the straight portions of the ribs 28^c with the thickened corner portions 18^c instead of the angular extensions of said ribs which are 10 aligned with the ribbing 27^c. Except as specifically described, the present embodiment may correspond with that of Figures 9 to 14, inclusive.

Referring now to the embodiment of my invention illustrated in Figures 20, 21 and 22, there is disclosed a cast spring plate 15^d which is only fragmentarily illustrated, as said plate is symmetrical about the center lines represented by the section lines 21—21 and 22—22. The plate 15^d differs from the plate of Figures 15, 16 and 17 in 20 that the peripheral ribbing 30^d and 31^d is generally parallel to the diagonals between opposite corner portions 18^d rather than being curved, the inner portions of said ribbing, however, being connected by curved portions 37 and 38, respectively. A further distinction resides in the fact that the straight portions 29^d of the ribbing extend from the angular ends of the relatively high ribbing 28^d, which completes the rectangular spring band surrounding portion comprising the ribbing 27^d, instead of being aligned with the ribbing 28^d. In the present embodiment, the web portion 26^d surrounded by the ribbing 27^d, 28^d is thinner and preferably concavely curved on its upper surface like the web portion 26 of the first embodiment, rather than being flat like the web portion 26^b of the embodiment of Figures 15, 16 and 17. Except as specifically described, the plate 15^d may correspond with the plate 15^b of the embodiment of Figures 15, 16 and 17. 40

Referring now to the embodiment of my invention illustrated in Figures 23 to 26, inclusive, there is disclosed a cast spring plate 15^e which is only fragmentarily illustrated as said plate is symmetrical about the center line represented by the uppermost element of the section line 24—24. The plate 15^e differs from the plate 15 of the first embodiment in that there is no flattening of the thickened corner portions 18^e, and two nibs 33^e rather than one are provided on the gusset portions 32^e. A further distinction resides in the fact that the web portion 34^e of the plate extends outwardly from the top of the relatively high ribbing 28^e instead of extending diagonally from the main web 23^e of the plate, said web portion 34^e 55 being generally parallel to the web portion 23^e, with the end portions, however, sloping toward the web portion 23^e to finally merge therewith, as indicated at 39. As in the embodiment of Figures 20, 21 and 22, the ribbing 28^e has straight 60 portions 29^e extending straight out from the angular end portions of said ribbing, tapering and merging into the web portion 23^e with the web portions 39. As in the first embodiment, the rectangular spring band centering ribbing is completed by straight ribbing 27^e which is not as tall as the ribbing or web connecting portions 28^e of the plate. As in the first embodiment, the web portion 26^e surrounded by the rectangular portion 65 27^e, 28^e is generally thinner and at least partially cylindrically concave on its upper face. 70

It will be seen that the elevation of the web portions 34^e provides for clearing the spring plank corrugations or frame reinforcements like the diagonal formation of portions of the webs of the 75

preceding embodiments. Except as specifically described, the present embodiment may correspond with that of the first embodiment.

From the foregoing disclosure, it will be seen that I have devised a spring plate, represented by several embodiments, which is adapted to positively retain the associated band of an elliptic or plate spring in normal position. Although I have shown my plate as separate from the adjacent bolster, spring plank or frame, associated with both coil and elliptic springs, and both above and below said springs, it will be understood that I do not wish to be limited to this showing, as, for example, the helical spring centering collars or ribbing and/or the generally rectangular spring-band-positioning ribbing may be formed integral on the bolster and/or spring supporting portion of the side frame, or spring plank if used, and the plates omitted, resulting in what amounts to a merger of said plates with the bolster and frame or plank. Other modifications may, likewise, occur to those skilled in the art. As indicated in the embodiments, the coil springs may be centered by outer or inner flanges and the reinforcing ribbing on the web of the plate, bolster, spring plank or frame may be varied to some extent.

Although the coil spring seats or supporting portions of the plates are shown thicker than the elliptic spring seats, I do not wish to be limited to this showing, as I contemplate forms in which the seats for the two forms of springs are of the same thickness, and also in which the seats for the coil springs are thinner than those for the elliptic spring or springs. It will also be understood that although the elliptic spring bands are shown centered and surrounded by generally rectangular ribbing, the smaller ribbing, as designated by the reference character 27 in Figs. 1 to 8, inclusive, may be omitted, leaving the larger or taller ribbing 28 only, with its angular extensions, or the ribbing may be otherwise discontinuous or segmental, with portions, however, desirably lying on all four sides of the associated spring band, for properly positioning the elliptic spring or banded leaf springs.

Although preferred embodiments of my invention have been illustrated, it will be understood that additional modifications may occur to those skilled in the art within the spirit and scope of the appended claims.

50 I claim:—

1. A spring nest adapted for insertion in the bolster opening of a railway vehicle side frame for the support of an associated bolster comprising upper and lower plates formed to center both helical springs and leaf springs held together by band means, said plates for that purpose having relatively thick corner portions adapted to center said helical springs, and thinner web portions connecting said corner portions and provided with ribbing, said ribbing comprising rectangular generally central portions formed to center the bands of said leaf springs.

65 2. A spring nest adapted for insertion in the bolster opening of a railway vehicle side frame for the support of an associated bolster comprising upper and lower plates formed to center both helical springs and leaf springs held together by band means, said plates for that purpose having relatively thick corner portions adapted to center said helical springs, and thinner web portions connecting said corner portions and provided with ribbing, said ribbing comprising rectangular generally central portions formed to center the bands of said leaf springs, those portions of the webs

surrounded by said rectangular portions being generally thinner than the web portions outwardly thereof.

3. A spring plate for a truck spring unit provided with relatively thick corner portions adapted to center helical springs, and thinner web portions connecting said corner portions and provided with ribbing, said ribbing comprising a rectangular generally central portion formed to center a band of an associated banded leaf spring.

4. A spring plate for a truck spring unit involving both helical and leaf springs held together by band means, said plate comprising relatively thick corner portions adapted to center said helical springs, and thinner web portions connecting said corner portions and provided with ribbing, said ribbing comprising a rectangular generally central portion formed to center a band of said leaf springs, that portion of the web surrounded by said rectangular portion being generally thinner than the web portion outwardly thereof.

5. A spring plate for a truck spring unit comprising corner portions adapted to center helical springs, and web portions connecting said corner portions, said web portions having a generally rectangular rib with end portions of greater height than the sides in order to engage alongside the adjacent leaf of a banded leaf spring, as well as surround the band of said spring.

6. A spring plate for a truck spring unit comprising corner portions formed to center helical springs, and a web portion connecting said corner portions, said web portion having reinforcing ribbing thereon disposed generally parallel to the diagonal axes through opposite corner portions.

7. A spring plate for a truck spring unit comprising corner portions formed to center helical springs, and a web portion connecting said corner portion, said web portion having ribbing thereon formed generally rectangular in plan for centering a banded leaf spring by surrounding the band thereof, said web being reinforced by ribs extending from approximately the corners of said rectangular ribbing outwardly to the corner portions with the outer portions of said ribs positioned approximately on the axes joining opposite corner portions of said plate.

8. A spring plate for a truck spring unit provided with corner portions adapted to center helical springs and web portions connecting said corner portions and provided with rectangular ribbing for centering a band of an associated banded leaf spring, said corner portions being connected by ribbing extending over the face of said web, portions of said web extending outwardly of said ribbing, and nibs disposed, at least in part beyond said ribbing, for centering said plate.

9. A spring plate for a truck spring unit provided with corner portions adapted to center helical springs, and web portions connecting said corner portions and provided with ribbing generally rectangular in plan for centering a banded leaf spring, that portion of said web inside of said rectangular ribbing being generally cylindrically concave to allow the band to nest therewith.

10. A spring plate for a truck spring unit provided with corner portions adapted to center helical springs, and a web portion connecting said corner portions and provided with ribbing thereon, said corner portions having serrated ribbing around the periphery thereof for centering helical springs and uniting with ribbing on the connecting web portion of said plate.

11. A spring plate for a truck spring unit pro-

vided with corner portions adapted to center helical springs, and a web portion connecting said corner portion and provided with ribbing thereon, said ribbing comprising relatively high side

5 portions and relatively low side portions uniting and forming a generally rectangular portion for centering an associated banded leaf spring, said high ribbing portions being extended outwardly by tapering ribbing which finally merges into 10 the web portion of the plate.

12. A spring group for use in truck side frames comprising leaf springs held together by bands, said spring group being defined at one end by a multiplicity of spring bearing surfaces, cast 15 means providing a seat for, and with lateral restraining means lying on four sides of, a band, said cast means forming a load carrying element of the truck, and a separate cast member for the opposite end of said spring group, said separate 20 cast member embodying lateral restraining means lying on four sides of the other band of the group, the opposite face of said separate cast member being relatively flat to afford a shimming surface.

25 13. A spring nest adapted for insertion in the bolster opening of a railway vehicle side frame for the support of an associated bolster comprising upper and lower plates formed to center helical springs and leaf springs held together by 30 band means, said plates for that purpose having corner portions of a thickness different from that of the remainder of the plate and adapted to center said helical springs, and web portions connecting said corner portions and provided with 35 ribbing, said ribbing comprising portions lying on all four sides of the band means of said leaf springs.

14. A spring plate for a truck spring unit comprising corner portions adapted to center 40 helical springs, and web portions connecting said corner portions, said web portions having ribs adapted to lie on four sides of the band of a leaf spring to prevent lateral shifting thereof, the ribs on two opposite sides being of greater 45 height than those on the other sides in order to engage alongside the adjacent leaf of said spring.

15. A spring plate for a truck spring unit provided with corner portions adapted to center helical springs and a web portion connecting said 50 corner portions and provided with ribbing thereon, said ribbing comprising spaced relatively high side portions and spaced relatively low side portions lying on opposite sides of a generally rectangular seat for a band of an associated leaf spring, said ribbing serving to maintain said band in proper position, said ribbing portions joining with tapering ribbing which finally merges into the web portion of the plate.

16. A nest of springs adapted for insertion in 55 the bolster opening of a railway vehicle side frame to support an associated bolster, said nest comprising helical springs and leaf springs held together by band means, and means associated with said bolster and that portion of said frame beneath said opening for centering said helical springs and the band means of said leaf springs, said means including cast ribbing lying on all 60 four sides of each seat for the spring band means to prevent lateral shifting thereof.

70 17. A spring plate for a truck spring unit comprising corner portions formed with annular beading for centering helical springs, and a web portion connecting said corner portions, said web portion having reinforcing ribbing thereon at 75 least portions of which are parallel to other por-

tions, at least some of said reinforcing ribbing merging with ribbing adapted to lie on four sides of the band of an associated banded leaf spring for centering purposes.

18. A spring plate for a nest of bolster springs comprising helical springs and leaf springs held together by bands, said plate comprising corner portions of a thickness different from that of the remainder of said plate and adapted to center said helical springs, and a web portion connecting 10 said corner portions with ribbing, said ribbing comprising portions lying on four sides of the engaging band of said leaf springs.

19. A spring plate including a body portion having a centrally disposed spring band seat and 15 coil spring seats spaced on opposite sides thereof, said spring band seat being defined by projections adapted to extend on each side of a spring band, a portion of said projections being offset to clear a tension member of a double truss side 20 frame.

20. A spring plate including a body portion having a centrally disposed spring band seat and coil spring seats disposed on opposite sides thereof, said spring band seat being defined by 25 spaced lugs upwardly offset from said body portion, to clear a tension member of a double truss side frame.

21. A spring plate including a body portion having a centrally disposed spring band seat and 30 coil spring seats disposed on opposite sides thereof, said spring band seat being defined by projections adapted to extend on each side of a spring band, a portion of said projections being offset to clear a tension member of a double truss 35 side frame, said spring band seat being disposed at a different level from said coil spring seats.

22. In a truck, the combination of a side frame including tension and compression members and 40 integrally connecting columns forming a window therewith, a portion of said tension member extending into said window, a load carrying member extending into said window and slidably cooperating with said columns, said load carrying member having spaced coil spring positioning means disposed adjacent coil spring seats, a spring band seat between said positioning means, a spring group including coil springs positioned by said positioning means, a leaf spring 45 engaging said band seat, said band seat being disposed at a different level from said coil spring seats, a spring plate carried by said side frame, said spring plate including a spring band seat 50 engaging and supporting a band of said leaf spring, and spaced dowels disposed adjacent said coil spring seats received by said coil springs 55 said band seat including an upwardly projecting portion disposed to clear the portion of a tension member in said window and forming a centering means for said band.

23. In a truck, the combination of a side frame including tension and compression members and integrally connecting columns forming a window therewith, a portion of said tension member extending into said window, a load carrying member 60 extending into said window and slidably cooperating with said columns, said load carrying member having spaced dowels disposed adjacent coil spring seats, a spring band seat between said dowels, a spring group including coil springs 65 positioned by said dowels, a leaf spring having a band engaging said band seat, a spring plate carried by said side frame, said spring plate including a spring band seat 70 engaging and supporting a band of said leaf spring, and spaced

dowels disposed adjacent said coil spring seats received by said coil springs, said spring band seat being defined by spaced lugs embracing said spring band and including an upwardly projecting portion disposed to clear the portion of a tension member in said window and forming a centering means for said band.

24. In a truck, the combination of a side frame including tension and compression members and integrally connecting columns forming a window therewith, a portion of said tension member extending into said window, a load carrying member extending into said window and slidably cooperating with said columns, said load carrying member having spaced dowels disposed adjacent coil spring seats, a spring band seat between said dowels, a spring group including coil springs positioned by said dowels, a leaf spring having a band engaging said band seat, a spring plate carried by said side frame, said spring plate including a spring band seat engaging and supporting a band of said leaf spring, and spaced dowels disposed adjacent said coil spring seats received by said coil springs, said spring band seat being defined by spaced lugs embracing said spring band, a portion thereof being offset upwardly from the base of said spring plate to clear the portion of a tension member in said window and forming a centering means for said band.

25. In a truck, the combination of a side frame including tension and compression members and integrally connecting columns forming a window therewith, a portion of said tension member extending into said window, a load carrying member extending into said window and slidably cooperating with said columns, said load carry-

ing member having spaced dowels disposed adjacent coil spring seats, a spring band seat between said dowels, a spring group including coil springs positioned by said dowels, a leaf spring having a band engaging said band seat, and a spring plate carried and positioned by said side frame, said spring plate including a spring band seat engaging and supporting a band of said leaf spring said band seat including an upwardly projecting portion disposed to clear the portion of a tension member in said window and forming a centering means for said band.

26. In a truck, the combination of a side frame including tension and compression members and integrally connecting columns forming a window therewith, a portion of said tension member extending into said window, a load carrying member extending into said window and slidably cooperating with said columns, said load carrying member having spaced dowels disposed adjacent coil spring seats, a spring band seat between said dowels, a spring group including coil springs positioned by said dowels, a leaf spring having a band engaging said band seat, a spring plate carried by said side frame, said spring plate including a spring band seat engaging and supporting a band of said leaf spring, and spaced dowels disposed adjacent said coil spring seats received by said coil springs, said last named coil spring seats being disposed at a higher level than said last named band seat said band seat including an upwardly projecting portion disposed to clear the portion of a tension member in said window and forming a centering means for said band.

DONALD L. TOWNSEND.
